CAR ROOF

Charles David Bonsall, Pittsburgh, Pa., assignor
to P. H. Murphy Company, New Kensington,
Pa., a corporation of Pennsylvania

Application October 28, 1936, Serial No. 107,938

8 Claims. (Cl. 108—5.4)

My invention relates to metal car roofs and particularly to that type of car roof wherein the roof sheets span from side plate to side plate and are formed into a longitudinal series of alternating upper and lower panels. Principal objects of the invention are to minimize the vertical space occupied by the roof, to locate the roof as high above the rails as the established tunnel clearance line will permit, to provide for the replacement of roofs of old cars with new roofs at a higher level so as to increase the storage capacity of the car, and to provide a runway at the ridge of the car without increasing the overall height of the car. The invention consists in the construction and in the parts and arrangements and combinations of parts hereinafter described and claimed.

In the accompanying drawings which form part of this specification and wherein like reference numerals refer to like references wherever they occur,

Fig. 1 is a fragmentary plane view of a car roof embodying my invention;

Fig. 2 is a vertical transverse section through one-half of the roof on the line 2—2 in Fig. 1;

Fig. 3 is a vertical longitudinal section through the roof at the ridge;

Fig. 4 is an enlarged vertical transverse section similar to Fig. 2 through the eaves portion of the car;

Fig. 5 is a vertical transverse section at the ridge on the line 5—5 in Fig. 1;

Fig. 6 is a similar section on the line 6—6 in Fig. 1;

Fig. 7 is a section similar to Fig. 6 showing a slightly modified construction; and

Fig. 8 is a view similar to Fig. 4, showing another modification.

The construction illustrated in the accompanying drawings comprises metal side plates A of the car, metal carlines B, whose ends are secured to the respective side plates, and metal roof sheets C, whose ends are bent down and secured flatwise to the outer faces of the respective side plates.

The side plates illustrated in the drawing are of Z-shape with the web portion 1 disposed horizontally and with its inner flange or leg 2 extending upwardly and its outer flange or leg 3 extending downwardly.

The body member 4 of the carline illustrated in the drawings is in the form of an inverted channel with outwardly extending flanges 5 along its lower margins. This body member is of substantially uniform cross section through-

out the main portion thereof but, at some distance inwardly from each end, there is a break 6 or change of direction in its lower surface, whereby the depth of the body member of the carline decreases from such breaks to each end 5 of said body member.

The body member of the carline is shaped so that its upper surface is substantially parallel with the established tunnel clearance outline (indicated by broken lines X) except that opposite the angles or breaks in said outline, the upper surface of the carline is rounded, as indicated at 7, 8 to connect the adjacent straight stretches, 9, 10, 11, of said surface.

Each carline has end members 12 riveted or otherwise secured to its body member. As illus-

trated in Fig. 4, the end member is in the form of a bracket with a vertical leg 12a disposed flatwise against the outer face of the upstanding inner leg 2 of the side plate, and with an inwardly and upwardly inclined leg 13 at the top of said vertical leg 12a. The inner portion of the inclined leg 13 constitutes a seat 14 for the end of the body member, which rests flatwise thereon and is rigidly secured thereto, as by rivets 15 ex-

tending through its lateral flanges 5. Preferably the portion 16 of the inwardly extending leg of the bracket between said seat 14 and the vertical leg is pressed up, as shown in Fig. 4, in angular form to afford a wide bearing for the eaves 20 portion of the overlying roof sheet; but this pressed up portion may be omitted, as shown in Fig. 8. The sheet-bearing portion of the sloping leg of the bracket parallels the adjacent portion 25 of the established tunnel clearance outline, while the carline seat portion of said leg is low enough to make the upper surface of the body member of the carline flush with the upper surface of

said sheet-bearing portion.

The roof sheets C illustrated in the drawings are of the neutral axis type wherein the roof sheets are organized into a longitudinal series of

ribs alternating with channels which cooperate in carrying the roof load after the manner of a beam supported on the side plates. In the con-

struction illustrated, the margins 17 of adjacent sheets rest on the body member of a carline and are welded thereto and to each other by welds 18 which fill the space between them. The middle portion 19 of each sheet is depressed longitudinally 30 of the sheet to form the channel or lower panel of the sheet. As shown in Fig. 4, the depth of the channel begins to decrease at a point along the line of the breaks 6 in the end portions of the carlines and continues to decrease to the vanish-

ing point, which is preferably along the line where the sheet starts to curve downwardly over the side plate.

- As in the case of the carlines, the roof sheets 5 are pressed or shaped with reference to the tunnel clearance outline established by the American Association of Railways. The upper panels of the sheets are shaped to have their margins rest flatwise on top of the carlines. 10 Assuming that the outer surface of the roof sheet, at the outermost point of contact of said sheet with the carline bracket, coincides with the tunnel clearance outline, said sheet has a stretch 15 20 which slopes inwardly and upwardly, at the same angle as the clearance outline and with the upper surface of the sheet substantially coinciding with said outline, to a point near the break 21 in said outline, from which point the sheet curves upwardly and inwardly, after the manner of the 20 carline, to a point beyond said break, where the upper surface of the sheet again coincides with the clearance outline and has a straight stretch 22 which follows said outline to a point somewhat outwardly beyond the next break 23 in the clearance 25 outline. From this point, the sheet again curves upwardly and inwardly beyond said break and merges into a straight horizontal stretch 24 which extends beyond the longitudinal center line of the car. The other half of the sheet is 30 the same as that just described. It is noted that the horizontal ridge stretch 24 of the sheet does not coincide with the established clearance line but is far enough below the same to accommodate the runway hereinafter described. 35
- In order to provide a runway, the spaces between adjacent roof ribs are bridged by members 25 disposed in the channels with their upper surfaces substantially flush with the upper surfaces of the roof ribs. In the construction illustrated, such member comprises a plate with downturned marginal flanges 26, the end flanges being preferably welded to the sides of the channel. The longitudinal middle portion of the runway member has a hollow channel or depressed 40 45 rib 27 formed therein and the longitudinal margins 28 of the member are paneled or raised slightly. The channel or hollow of the longitudinal rib is filled with mastic asphalt 29 or like plastic material which, when dry, will adhere to the metal and has a fair degree of tensile strength which may be increased by fibrous or like reinforcement. This mastic asphalt is also spread over the body portion of the runway member and preferably has sand or other coarse material 50 55 embedded therein to roughen the surface thereof and prevent slipping of the trainmen thereon. The layer of plastic material is made as thin as practicable and the raised side margins of the runway sections protect the edges of said material from being injured or raised accidentally. 60

The portions of the roof ribs between the runway sections 25 are also covered with plastic material 29a which functions as part of the runway. In the construction shown in Fig. 6, the roof ribs are depressed, as at 30, to provide depressed seats for said material; but these depressed seats may be omitted, as shown in Fig. 7.

In the construction hereinbefore described, the 70 roof sheets and the carlines cooperate in taking care of the usual roof stresses and thus enable the roof to be made of shallow depth; and the manner in which the runway is provided for enables the roof to be raised substantially to the 75 maximum height above the rails permitted by the

established tunnel clearance outline, while the cross sectional shape of the roof, along with the features mentioned, provide maximum stowing capacity for the car. It is a great advantage of this roof that the sheets are continuous from side plate to side plate and that they require little work to conform them to the established clearance outline. Another advantage is that the end portions of the roof sheets curve down gradually into vertical position and are secured against the side plate by horizontal rivets, thus enclosing the tops of the side plates, guarding against the lodging of cinders and moisture on the side plates and the end portions of the roof sheets, avoiding the danger of leakage through the bolt holes, and disposing the metal of the sheets to good advantage in resisting the stresses to which it is exposed in service. It is also an advantage of the invention that the roof sheets are not only supported directly on the side plates but that the eaves portions thereof have wide bearings on the carline brackets. The invention has the special advantage that it is applicable to the replacement of roofs of old cars and makes it practicable to increase the capacity of such old cars by substituting new carlines or new carline brackets for those of the old car. Another important advantage is that it provides a runway that occupies a minimum of vertical space and is especially adapted to prevent slipping of the trainmen. 10 15 20 25 30 35 40 45 50 55 60 65 70 75 80 85 90 95 100

What I claim is:

1. A car roof comprising side plates having an upstanding inner leg and a downwardly extending outer leg, upstanding brackets secured to and extending above said inner legs, and roof sheets extending from side plate to side plate and resting on said brackets and whose ends are rigidly secured flatwise against the outer legs of said side plates. 40

2. A car roof comprising side plates having an upstanding inner leg and a downwardly extending outer leg, upstanding brackets secured to and extending above said inner legs, and roof sheets resting on said brackets and whose ends are secured flatwise against the outer legs of said side plates and said sheets having their longitudinal middle portions depressed for a distance substantially equal to the distance between the brackets on opposite sides of the car. 45 50 55 60 65 70 75 80 85 90 95 100

3. A car roof comprising side plates having an upstanding inner leg and a downwardly extending outer leg, carlines with outwardly and downwardly extending end members secured to said inner legs, the top surfaces of the body portions of the carlines being substantially parallel with the established tunnel clearance outline, and roof sheets extending from side plate to side plate and whose side margins rest upon the tops of said carlines and the end members thereof, the ends of said sheets being secured flatwise against the outer legs of said side plates. 55 60 65 70 75 80 85 90 95 100

4. A car roof comprising side plates having an upstanding inner leg and a downwardly extending outer leg, carlines with downwardly extending end members secured to said inner legs, the top surfaces of the body portions of the carlines being substantially parallel with the established tunnel clearance outline, and roof sheets whose side margins rest upon and are secured together and to the tops of said carlines and the end members thereof, the ends of said sheets being secured flatwise against the outer legs of said side plates, and said sheets having their longitudinal middle portions depressed for a dis- 75 80 85 90 95 100

- tance substantially equal to the distance between the members at opposite ends of the carlines.
5. A car roof comprising side plates having an upstanding inner leg and a downwardly extending outer leg, carlines comprising body members and end brackets, the carline brackets being secured to and extending above the inner legs of the side plates and having inwardly extending portions which slope upwardly to form bearings for the 10 roof sheets and terminate in seats for the carline bodies far enough below said bearings to make the tops of said bodies flush with said bearings, the top surfaces of the body portions of the carlines being substantially parallel with the established 15 tunnel clearance outline, and roof sheets whose side margins rest upon and are secured to the tops of said brackets and carline bodies, the ends of said sheets being secured flatwise against the outer legs of said side plates.
20. 6. A car roof comprising side plates having an upstanding inner leg and a downwardly extending outer leg, carlines with downwardly extending end members secured to said inner legs, the top surfaces of the body portions of the carlines 25 having a long horizontal stretch at the middle, and two straight stretches on each side thereof close to and substantially parallel with the adjacent portions of the established clearance outline, said straight stretches being connected by curves 10 opposite the breaks in the clearance outline, and roof sheets extending from side plate to side plate and whose side margins rest upon and are welded together and to the tops of said carlines and end members, the ends of said sheets being secured 15 flatwise against the outer legs of said side plates.
7. A car roof comprising side plates having an upstanding inner leg and a downwardly extending outer leg, carlines with downwardly extending end members secured to said inner legs,

the top surfaces of the body portions of the carlines having a long horizontal stretch at the middle, and two straight stretches on each side thereof close to and substantially parallel with the adjacent portions of the established clearance outline, 5 said straight stretches being connected by curves opposite the breaks in the clearance outline, and roof sheets whose side margins rest upon and are secured to the tops of said carlines and whose middle portions are depressed transversely 10 of the roof, the ends of said sheets being secured flatwise against the outer legs of said side plates, runway sections spanning the depressions, and a layer of plastic material extending along the ridge over the runway sections and side portions 15 of the roof sheets.

8. A car roof comprising side plates having an upstanding inner leg and a downwardly extending outer leg, carlines with downwardly extending end members secured to said inner legs, the 20 top surfaces of the body portions of the carlines having a long horizontal stretch at the middle, and two straight stretches on each side thereof close to and substantially parallel with the adjacent portions of the established clearance outline, 25 said straight stretches being connected by curves opposite the breaks in the clearance outline, and roof sheets whose side margins rest upon and are secured to the tops of said carlines and whose middle portions are depressed transversely of the 30 roof, the ends of said sheets being secured flatwise against the outer legs of said side plates, runway sections spanning the depressions at the ridge and a runway of plastic material on said runway sections and the portions of the roof 35 sheets between said sections, the runway sections having raised longitudinal side margins and a longitudinal groove filled with said plastic material.

CHARLES DAVID BONSALL.
